Filed Mar. 30, 1959, Ser. No. 55,244

Term of patent 3½ years

(Cl. D81—10)

FIG. 1.

FIG. 2.

FIG. 3.

FIG. 4.

Figure 1 is a side elevational view of an electric fuel igniter showing my new design, a portion of the cord being broken for convenience of illustration;

Figure 2 is a front elevational view thereof;

Figure 3 is a rear elevational view thereof with a portion of the cord omitted for convenience of illustration; and

Figure 4 is a top plan view thereof with a portion of the cord broken away as in Figure 3.

The dominant features of the design reside in the portions shown in the full lines.

I claim:

The ornamental design for an electric fuel igniter, as shown and described.
